UNITED STATES PATENT OFFICE.

FRITZ FEHR, OF FORT LEE BOROUGH, NEW JERSEY.

DESIGN FOR LACE OR SIMILAR ARTICLE.

Application filed June 3, 1926. Serial No. 17,924. Term of patent 3½ years.

To all whom it may concern:

Be it known that I, FRITZ FEHR, a subject of the Republic of Switzerland, residing in the borough of Fort Lee, in the county of Bergen and State of New Jersey, have invented a new, original, and ornamental Design for Lace or Similar Article, of which the following is a specification, reference being had to the accompanying drawing, forming part thereof.

The figure is a plan view of a piece of lace showing my new design.

I claim:

The ornamental design for lace or similar article, as shown.

FRITZ FEHR.
